APPARATUS FOR SHAPING AND FORMING
LEATHER

Marty Green and Irving Sheroff, Brooklyn, N. Y.

Application June 11, 1946, Serial No. 676,059

6 Claims. (Cl. 69—8)

1

The invention deals with an improved and serviceable apparatus for shaping and folding non-metallic flexible material and specifically is concerned with an efficient apparatus for doubling back the peripheral margins of preformed flexible material or stock to characterize reinforced and finished edges. The dominant object of the invention resides in the provision of a novel apparatus wherein the flexible sheet material to be doubled back upon itself is initially shaped upon the displacement of a self retracting inner platen or pad downwardly relative to an outer spring controlled, self retracting normally elevated frame slidably guiding and closely surrounding the inner platen and wherein the shaped material or stock is subsequently folded or turned inwardly against the body of the stock upon displacement of the normally elevated shaping frame downwardly relative to the depressed inner platen by frame or boss means depending from an upper and reciprocable bending or forming head driven by a suitable ram of a punch press. Another object is concerned with the provision of means common to the inner reciprocable pad or platen and its surrounding reciprocable shaping frame to severally limit the depression thereof. Another object is to provide a novel method for shaping and folding flexible material or stock to reinforce the margins thereof. Other important objects, advantages, and functional and structural features of the invention will be apparent from the following detailed specification taken with the accompanying drawings wherein:

Fig. 1 is a perspective view of the apparatus according to our invention showing the die thereof in its normal or opened relation.

Fig. 2 is a view on the line 2—2 of Fig. 1 and illustrating a bottom view of the bending head and its depending frame.

Fig. 3 is a view on the line 3—3 of Fig. 1 showing the slidably guided inner platen or pad surrounded by the shaping frame.

Fig. 4 is a sectional view on the line 4—4 of Fig. 2.

Fig. 5 is a sectional view on the line 5—5 of Fig. 1.

Fig. 6 is a sectional view on the line 6—6 of Fig. 3.

2

Fig. 7 is a front view of Fig. 1 illustrating the die in its normally opened position, shown partly broken away and partly in section.

Fig. 8 is a view similar to Fig. 7 however illustrating the upper pad or platen initially clamping the flexible material or stock against the lower pad prior to shaping and folding.

Fig. 9 is a view similar to Fig. 8 however illustrating the lower pad or platen depressed by the upper platen and the flexible stock shaped and telescoped within the slidable shaping frame however prior to folding the upstanding peripheral margin.

Fig. 10 is a view similar to Fig. 9 but showing the lower pad held depressed by the upper platen and the bending or folding head depressing the shaping frame on turning down or bending the peripheral margin of the flexible stock.

Fig. 11 is a fragmentary view of Fig. 12 illustrating the marginal portions of the stock fully bent back upon the stock at which time the bending or folding head is fully depressed, and

Fig. 12 is a side view of Fig. 10 however illustrating the shaping frame fully depressed by the upper bending head.

Illustrative of the method and the preferred embodiment disclosed, the invention contemplates shaping flexible sheet material or stock S, such as fabric, plastic, or leather in initially lifting the margins M of the stock and thereafter bending or folding the margin M inwardly and downwardly against the body of the stock to provide an appropriate reinforced peripheral edge on the stock.

In the apparatus generally denoted P the stock S is initially positioned on a slidably guided pad or lower platen 10 with its outer margins M overlapping the upper surface of the shaping frame F which has an opening 11 corresponding in contour to the pad 10 and in which the latter is closely and slidably guided. As shown the pad 10 and the opening 11 is six sided or polygonal but other desired and corresponding shapes may be employed. As is well understood portions of the margins M overlying the frame F are interrupted by suitably disposed cuts or gaps not shown.

Normally the slidably guided pad or platen 10 is held flush with the upper surface of the shaping frame F and its outer margin is chamfered

or beveled to provide the peripherally arranged and inclined marginal faces 12.

The pad 10 fixedly but removably carries several posts 13 slidably guided in the base B. These posts are in part disposed in the large bores 14 in pad 10 and in part are slidably guided in the openings 15 in the base B.

Surrounding each post 13 is a normally expanded helicoidal spring 16 having its upper end confined in bore 14 and abutting the pad 10 and has its lower end abutting the base B which is fixedly anchored to support 17 of the apparatus P forming a part of a well known punch press.

The lower portions of the bore 15 in the base B are countersunk to provide sockets 18 for receiving the enlarged heads 19 of the slidably guided posts 13 and the upper walls of sockets 18 cooperate with heads 19 to limit upward displacement of the lower pad or platen 10 at which time the upper surface of pad 10 is flush with the upper surface of the slidably guided shaping frame F. If the pad 10 is depressed, helicoidal springs 16 are compressed. Upon removal of downwardly directed pressure on the pad 10, springs 16 automatically elevate or retract this pad until head 19 of posts 13 abut the upper wall of the sockets 18. Thus the pad 10 may be said to be normally elevated or spaced from the base B due to the action of the equalizing helicoidal springs 16.

Power springs 20 normally hold the slidably guided frame F retracted, namely, in spaced relation to the fixed base B. Each of these springs 20 surrounds a pin 21 having its upper end threadably connected to the shaping frame F while the lower ends threadably carry an adjustable stop nut 22. Each of these springs 20 has its lower major portion confined in the tubular housing 23 having its upper end carried by and threaded to the fixed base B. Each lower end of the housings 23 is threadably connected to a closure cup 24 having a centrally arranged opening 25 for slidably guiding its companion pin 21 when the frame F is displaced downwardly or upwardly retracted relative to the pad 10.

Extending upwardly from the base B and appropriately anchored thereto are the spaced posts 26 projecting into the spaced openings 27 of the shaping frame F for slidably guiding the latter relative to the base B. To further aid such action, the base embodies opening 28 slidably guiding post 29 fixedly carried by and depending from the frame F.

The reciprocable ram R of the punch press fixedly carries the upper bending or forming head H which slidably guides the reciprocable platen or upper pad 30 having a contour corresponding to the contour of the lower platen or pad 10 but smaller to be desirably and removably receivable in the opening 11 in the reciprocable frame F. Specifically, however, the upper platen or pad 30 has secured thereto the spaced posts 31 extending through the threaded openings 32 (Fig. 10) in the bending or folding head H. These posts are centrally or concentrically disposed within the hollow nipples 33 which embody an annular stop shoulder 34 slidably guiding posts 31 having enlarged heads 35 coacting with shoulders 34 to limit downwardly displacement of the platen 30 relative to bending head H.

Surrounding each post 31 and abutting shoulder 34 and platen 30 is a normally expanded helicoidal spring 36 for automatically holding the platen 30 fully depressed at which time heads 35 of the slidably guided posts 31 are against the

stop shoulders 34 and the springs 36 are fully expanded, and the reciprocable ram R is fully retracted within the fixed ram guide G (Fig. 7). Also at this time posts 26 which project above shaping frame F are out of or clear of the guide openings 37 in the bending head H.

Integral with and depending from the bending head H is the peripherally closed boss or frame 40 having its inner corner portions cut away to define a concaved or an arcuate face 41 merging with perpendicular wall 42 defining an opening 44 corresponding in contour to the lower platen or pad 10 to removably and slightly receive the pad 10 when the shaping frame F is fully depressed by the bending head H (Fig. 11).

To shape and form a sheet of flexible material or stock S, the latter is first mounted on the inner platen or pad 10 in the manner indicated in Fig. 7. The treadle (not shown) of the punch press is now actuated. By such action ram R is slidably displaced downwardly relative to the ram guide G. The upper platen 30 thus contacts and clamps the stock S against the lower platen 10. The ram continues on its down stroke and the springs 36 become compressed and ultimately the lower platen 10 is slidably displaced downwardly within the shaping frame F against the resistance of the springs 16 which now also become compressed. The upper platen 30 is now within the shaping frame F (Fig. 9). The lower platen 10 at this time has reached the limit of its downward stroke and is seated on the base B which serves as stop for the lower platen 10. On downward displacement of the lower platen 10, the margins M of the stock brush the wall of the opening 44 in the shaping frame F and instead of being in the general plane of the body of the stock S now are disposed substantially normal thereto as shown in Fig. 9 wherein the depending boss or frame 40 of the bending or folding head H is about to strike the elevated shaping frame F.

On continuation of the downward stroke of the ram R and after the lower platen 10 has struck the base B, boss 40 of the bending or forming head H meets the raised shaping frame F and depresses the latter against the resistance of the power or equalizing springs 20 (Fig. 10). The arcuate cam faces 41 of the boss 40 now bend the margins M inwardly and towards the stock S and on the complete downward displacement of the shaping frame F the stock is urged and seated against the beveled margins 12 of the lower platen or pad 10 (Fig. 11), the bending operation being facilitated by the upper portion 43 of the arcuate or cam face 41 which forces the turned down margin M against the stock S and the latter against the beveled margin 12 of the lower platen or pad 10. By such action the stock S is now desirably creased or bent back upon itself. This operation takes place at the completion of the downward stroke of the ram R at which time bending head H receives the lower platen 10 within the opening 44 defined by the depending boss 40. At such time both the shaping frame F and bending head H are in their fully depressed positions (Fig. 12). The same of course holds true for the lower pad 10. Following the bending or folding operation, the ram begins its return or upward stroke. Hence boss 40 leaves frame F and the latter is automatically elevated or retracted due to the expansion of the power springs 20. The lower platen 10 is also retracted automatically away from the base B and is restored to its normal

flush relation with the frame F by the springs 16. The upper platen is automatically projected downwardly due to the expansion of the spring 36 and at the completion of the retractive or upward stroke of the ram R the shaping and bending apparatus P is again in its fully opened position shown in Figs. 1 and 7 awaiting to receive another sheet of stock S to be shaped and bent as heretofore described.

From the foregoing disclosure it is apparent that the shaping and bending or folding operations are in effect carried out in first depressing a self retracting and spring controlled platen relative to a normally elevated and self retracting and spring controlled shaping frame and thereafter for purposes of bending or folding the shaped stock the shaping frame is depressed relative to the depressed lower platen by depending and cam shaped means of a bending or folding head carried by a reciprocable ram.

Pursuant to shaping and bending of the stock, the lower platen 10 in effect projects the processed stock out of the self retracting frame F and at no times does the upper bending head project within opening 11 of shaping frame F although at the completion of the bending operation the pad 10 and the shaping frame F are against the fixed base B which acts to severally limit downward displacement thereof.

Various changes may be made in the details of construction and arrangement of parts without departing from the spirit of the invention or sacrificing any of the advantages therein.

We claim:

1. In an apparatus for shaping and folding non-metallic flexible stock, a base, a pad for supporting said stock and slidable relative to said base, a shaping frame normally spaced from said base and for supporting marginal portions of said stock and including an opening for slidably guiding said pad, a platen receivable in said opening for clamping said stock against said pad and for driving said marginal portions along the wall of said opening to lift said marginal portions relative to the body of said stock, a head normally spaced from said shaping frame and slidably carrying said platen for driving the latter to depress said pad against said base, and means carried by said head for depressing said shaping frame relative to said pad when the latter is against said base and for folding said lifted marginal portions downwardly and against said stock.

2. In an apparatus for shaping and folding non-metallic flexible stock, a base, a pad normally spaced from said base for supporting said stock and slidable relative to said base, a shaping frame normally spaced from said base and for supporting marginal portions of said stock and including an opening for slidably guiding said pad, means for slidably guiding said frame relative to said base, a platen movably receivable in said opening for clamping said stock against said pad and for driving said marginal portions along the wall of said opening to lift said marginal portions relative to the body of said stock, a head normally spaced from said shaping frame and slidably carrying said platen for driving the latter to depress said pad against said base, and means carried by said head for depressing said shaping frame relative to said pad when the latter is against said base and for folding said lifted marginal portions downwardly and against said stock.

3. In an apparatus for shaping and folding non-metallic flexible stock, a base, a pad for supporting said stock and slidable relative to said base, means to resiliently sustain said pad normally spaced from said base, a shaping frame for supporting marginal portions of said stock and including an opening for slidably guiding said pad, means for slidably guiding said frame relative to said base, means to resiliently sustain said frame normally spaced from said base, a platen receivable in said opening for clamping said stock against said pad and for depressing said pad and for driving said marginal portions along the wall of said opening to lift said marginal portions relative to the body of said stock, a head normally spaced from said shaping frame and slidably carrying said platen for driving the latter to depress said pad against said base, and cam means carried by said head for depressing said shaping frame relative to said pad when the latter is against said base and for folding said lifted marginal portions downwardly against said stock.

4. In an apparatus for shaping and folding non-metallic flexible stock, a base, a pad for supporting said stock and slidable relative to said base, means to resiliently sustain said pad normally spaced from said base, a shaping frame for supporting marginal portions of said stock and including an opening for slidably guiding said pad, means for slidably guiding said frame relative to said base, means to resiliently sustain said frame normally spaced from said base, a platen receivable in said opening for clamping said stock against said pad and for depressing said stock against said pad and for depressing said pad and for driving said marginal portions along the wall of said opening to lift said marginal portions relative to the body of said stock, a head normally spaced from said shaping frame and slidably carrying said platen for driving the latter to depress said pad against said base, and a frame depending from said head for depressing said shaping frame relative to said pad when the latter is against said base and having means for folding said lifted marginal portions downwardly against said stock.

5. In an apparatus for shaping and folding non-metallic flexible stock, a base, a pad for supporting said stock and slidable relative to said base, means to resiliently sustain said pad normally spaced from said base, a shaping frame for supporting marginal portions of said stock and including an opening for slidably guiding said pad, means for slidably guiding said frame relative to said base, means to resiliently sustain said frame normally spaced from said base, a platen receivable in said opening for clamping said stock against said pad and for depressing said pad and for driving said marginal portions along the wall of said opening to lift said marginal portions relative to the body of said stock, a head normally spaced from said shaping frame and slidably carrying said platen for driving the latter to depress said pad against said base, and a boss depending from said head for depressing said shaping frame relative to said pad when the latter is against said base and having a reduced portion having means for folding said lifted marginal portions downwardly against said stock.

6. In an apparatus for shaping and folding non-metallic flexible stock, a base, a pad for supporting said stock and slidable relative to said base and including a sloping marginal portion, means to resiliently sustain said pad normally spaced from said base, a shaping frame

for supporting marginal portions of said stock and including an opening for slidably guiding said pad, means for slidably guiding said frame relative to said base, means to resiliently sustain said frame normally spaced from said base, a platen receivable in said opening for clamping said stock against said pad and for depressing said pad and for driving said marginal portions along the wall of said opening to lift said marginal portions relative to the body of said stock, a head normally spaced from said shaping frame and slidably carrying said platen for driving the latter to depress said pad against said base, and a frame carried by said head for depressing said shaping frame relative to said pad when the latter is against said base and having an opening for removably receiving said pad and hav-

ing means for folding said lifted marginal portion downwardly against said stock and the latter against said sloping marginal portion.
